PURIFICATION OF THIOPHENOLS BY TREATMENT WITH ALUMINUM THIOPHENOXIDES

Robert J. Laufer, Pittsburgh, Pa., assignor to Consolidation Coal Company, Pittsburgh, Pa., a corporation of Pennsylvania

No Drawing. Filed Apr. 20, 1959, Ser. No. 807,280

5 Claims. (Cl. 260—609)

This invention relates to the art of separating thiophenols from tar acids. More particularly it relates to purifying thiophenols contaminated with tar acids by selective reaction of the tar acids with aluminum thiophenoxides to form aluminum phenoxides.

By "tar acids" I refer to those constituents present in coal-tar distillates, certain cracked petroleum distillates and the like, often referred to collectively as "phenols," which are soluble in dilute caustic soda, giving sodium "cresylate." I particularly refer to a mixture of the simpler monohydric phenols boiling below about 230° C. and consisting almost entirely of a mixture of phenol, methylphenols (cresols) and dimethylphenols (xylenols), with lesser amounts occasionally present of ethylphenols and trimethylphenols.

At present, thiophenols are principally obtained from two sources: as a by-product from the caustic extraction of petroleum distillates and by synthetic methods starting with benzene. In one widely used direct synthesis technique, the benzene is converted to benzene sulfonyl chloride by treatment with a molar excess of chlorosulfonic acid. The product is then converted to thiophenol by reduction in the presence of a metal-acid system. While the resulting product is of high purity, and particularly useful for paint, dyestuffs, and pharmaceutical applications, it is relatively expensive. This prevents its widespread use for many applications.

In obtaining thiophenols from petroleum distillates resulting from oil-cracking processes, the tar acids and thiophenols are recovered by extracting the petroleum distillate with aqueous caustic solution to produce water-soluble tar acid salts. In this process of extraction, thiophenols present are also removed by the aqueous caustic solution inasmuch as the thiophenols are even stronger acids than the phenols or tar acids themselves. The quantity of thiophenols in the original source material varies widely, being sometimes as little as one percent by weight of the phenols and ranging as high as 25 percent and above. The thiophenols consist principally of thiophenol itself and mixed thiocresols and thioxyleneols.

In U.S. Patent 2,767,220, a process is set forth for purifying thiophenol-contaminated tar acids that are substantially free of neutral hydrocarbon oils. In this process, the feedstock, consisting principally of tar acids and thiophenols, is contacted with aqueous methanol and with a low boiling paraffinic naphtha fraction in a continuous countercurrent extraction zone. The aqueous methanol solution dissolves substantially all the tar acids, and the naphtha fraction dissolves the thiophenols. The naphtha fraction is distilled off to yield the thiophenols as still bottoms. Inasmuch as the purification of the tar acids is the desideratum of this process, the thiophenols recovered from the paraffinic naphtha fraction invariably contain from 2 to 20 percent tar acids by weight. Complete removal of the tar acids from the thiophenols does not take place even when the thiophenols are fractionally distilled in a highly efficient column, such as a 50-plate packed tower. Thiophenol from such a distillation contains ap-

2

proximately 1.5 percent phenol. Efficient fractional distillation is likewise unsuccessful in effecting a removal of the tar acids from the mixed thiocresols and thioxyleneols. These thiophenols contain even higher amounts of close-boiling tar acids.

The process of the present invention provides a thiophenol of improved purity with respect to tar acid content. In accordance with this invention, a mixture of thiophenols and tar acids is treated with a preformed aluminum salt of a thiophenol. A rapid and irreversible interchange of the aluminum thiophenoxide with the tar acids then occurs whereby the tar acids selectively form aluminum phenoxides. The thiophenols are then separated from the relatively nonvolatile aluminum phenoxides, preferably by distillation. A preferred aluminum thiophenoxide reactant for use in the present invention is the aluminum salt of the thiophenol that is present. Thereby the only thiophenolic by-product of the interchange is the same as the thiophenol being purified.

It has been found that this method is suitable for rendering thiophenols containing tar acids in amounts up to 50 percent by weight of the mixture substantially free from tar acid contamination. The method is particularly preferred where the thiophenol has a tar acid content of up to 20 percent by weight of the mixture. In general, where thiophenol itself is to be purified, the contaminant present is usually phenol. It is believed that an azeotrope is formed thereby preventing the separation of the thiophenol and phenol by conventional distillation techniques. Mixed thiocresols are usually contaminated with o-cresol. The thioxyleneols generally contain a contaminating amount of close-boiling cresols and xylenols. This process is particularly useful for purifying tar acid-contaminated thiophenol, thiocresols, and thioxyleneols.

In my copending application Serial No. 747,589, filed July 10, 1958, are described various techniques for preparing aluminum thiophenoxide salts. In general, a preferred method involves preparing an aluminum amalgam, preformed or formed in situ. In a preferred method for preforming an active aluminum amalgam, granular aluminum (20-30 mesh) is contacted with a saturated ethereal solution of mercuric chloride for about 0.5 minute at the boiling point of the solution. The supernatant liquor is then quickly decanted, and the aluminum is washed by decantation with two portions of dry ether. The amalgamated aluminum should be prepared just prior to reaction with the thiophenol to form the aluminum thiophenoxide. As an illustrative example of the preparation of aluminum thiophenoxide, 30 grams of an aluminum amalgam prepared as above were rapidly transferred to a 5-liter flask fitted with a stirrer, a thermowell, and an efficient reflux condenser. Thiophenol (98 percent assay), 2960 grams, was added, and the apparatus was purged with nitrogen. Reaction commenced at 100° C. and became extremely vigorous at 121° C. The temperature rapidly rose to 145° C. even though the heating mantle was removed. Gas evolution ceased after 20 minutes.

A total of 2131 grams of thiophenol was then recovered by distillation on a steam bath, with stirring, at 15 mm. The residual slurry was cooled and treated with 500 ml. of hexane. Stirring was continued for one hour, and the slurry was rapidly filtered. The cake was washed with a small amount of hexane and then was transferred to a vacuum desiccator for drying at 5 mm. for several hours. Undue contact with air was avoided throughout the process. The dried cake, a grayish-white powder, weighed 412.7 grams or 104 percent of theory based on aluminum.

The aluminum amalgam is preferably formed in situ by treating aluminum with an inorganic mercury salt,

such as mercuric chloride or cyanide, together with the thiophenol whose aluminum salt is to be prepared. A temperature between 30 and 175° C. is preferred for the reaction between the aluminum and the thiophenol. A reaction product of aluminum and a thiophenol may also be prepared by reacting aluminum directly with a thiophenol in the absence of a mercury compound. However, to accomplish this, reaction at superatmospheric pressure at a temperature between 200 and 400° C. is required.

Upon addition of the aluminum thiophenoxide salt to the mixture of thiophenol and tar acid, preferably in an amount sufficient to provide at least $\frac{1}{3}$ gram atom of aluminum per gram mole of phenol present in the thiophenol, an almost immediate exothermic reaction occurs. If moisture is present, additional amounts of aluminum thiophenoxide are required. However, an excess of aluminum thiophenoxide above the stoichiometric amount is ordinarily not required for substantially complete removal of the tar acids if moisture is not present.

If addition of aluminum thiophenoxide per se, for example, is made at room temperature to a mixture of thiophenol and phenol, the solid aluminum thiophenoxide almost immediately begins to dissolve in the mixture of thiophenol and phenol. Although aluminum thiophenoxide is not very soluble in cold thiophenol, a sufficient amount dissolves to react with phenols present to form aluminum phenoxide. Since this reaction is exothermic, the evolution of heat further promotes solution of the thiophenoxide. This reaction is therefore seen as capable of occurring at a temperature range of from 0 to 200° C., particularly because of its exothermic nature. The greater the proportion of phenols present, the more rapid is the reaction. Also, the reaction is initiated at a lower temperature and proceeds more vigorously than when a lower concentration of phenol is present. The reaction is ordinarily complete within several seconds to several minutes, depending upon the initial temperature employed. In the course of the reaction, no evolution of hydrogen occurs, but an interchange of aluminum occurs so that upon use of a stoichiometric amount of aluminum thiophenoxide, all the tar acids present are combined with the aluminum.

This procedure offers the advantage that temperatures above those used for vacuum distillation are not required. Further, no hydrogen evolution occurs in situ during formation of the aluminum phenoxide. Also the only by-product of the interchange is a thiophenol. By starting with a preselected aluminum thiophenoxide, the desired thiophenol will be thereby obtained.

In general, a preferred method of preparing aluminum thiophenoxide salts is by reaction of aluminum metal with a thiophenol in the presence of an inorganic mercury salt. Where the subsequent presence of the mercury may be undesirable, the aluminum thiophenoxide may still be prepared in the presence of the mercury salt, and most of the formed mercury may then be readily removed by simple mechanical separation. To remove remaining traces of mercury, the thiophenoxide may be dissolved in thiophenol, and the mercury separated therefrom by filtration or high-speed centrifugation. The thiophenol is then removed by distillation. Or the aluminum thiophenoxide containing traces of mercury may be used as such, the mercury being subsequently removed from distillate fractions of the purified thiophenol.

The following examples illustrate this invention but are not intended as limitations thereof:

Example 1

Reaction of aluminum thiocresoxide with thiocresol-phenol mixture.—An amount of 465 grams of mixed thiocresols free from tar acids and 1.80 grams of mercuric chloride were heated to 165° C. Fifteen grams of granular aluminum and an additional 0.40 gram of mercuric chloride were added in portions to maintain a vigorous

reaction. The reaction was complete after one hour. Approximately 208 grams of the thiocresols originally present combined with the added aluminum to form aluminum thiocresoxide.

5 The reaction mixture was then cooled to 105° C., and 126 grams of phenol was added. The temperature rose sharply to 129° C. because of the exothermic nature of the reaction that occurred. The resulting dark, clear solution was maintained at 100° C. for one hour; the 10 pressure was then gradually reduced until 405 grams of distillate was collected. The distillate consisted of 100 percent thiocresol as determined by vapor-phase chromatography. No phenol was detectable. The latter, however, was readily recovered from the residual aluminum salts by hydrolysis.

Example 2

Conversion of aluminum thiocresoxide to aluminum o-cresoxide.—A mixture of 188 grams (0.474 mole) of

20 aluminum thiocresoxide, prepared by the reaction of aluminum and mixed thiocresols, and 208 grams (1.92 moles) of o-cresol was distilled to a pot temperature of 200° C. at 5 mm. Hg. The overhead product contained 156 grams (1.26 moles) of thiocresols and 66 grams (0.612 mole) of o-cresol. The nonvolatile residue weighed 172 grams. Thus the conversion of aluminum thiocresoxide to an aluminum salt of o-cresol was at least 89 percent.

Example 3

Exothermic and irreversible nature of aluminum thiophenoxide interchange.—Excess tar acid-free mixed thiocresols, 465 grams (3.74 moles), were reacted with 15.00 grams (0.556 gram-atom) of aluminum in the presence of mercuric chloride. On completion of the reaction, the 35 temperature was lowered to 105° C. at which point the aluminum thiocresoxide formed a light gray slurry in the excess thiocresols. The unreacted thiocresols were removed by distillation under vacuum. To a mixture consisting of 248 grams (2.00 moles) of dry mixed thiocresol isomers and 126 grams (1.34 moles) of dry phenol was then added the previously prepared aluminum thiocresoxide. A dark, clear solution formed instantly and the temperature rose sharply to 129° C., thus indicating a significantly exothermic reaction. (In a separate experiment, a similar temperature rise occurred on the addition of o-cresol to aluminum thiophenoxide and thiophenol.) The reaction mixture was maintained at 100° C. for one hour. Finally, 409 grams (3.29 moles) of pure thiocresols was recovered by a Vigreux distillation

40 of the reaction mixture to a pot temperature of 105° C. at 10 mm. Hg. All of the phenol remained in the pot residue despite its lower boiling point (105° C./50 mm. Hg) as compared to that of the thiocresols (108° C./50 mm. Hg). The result is interpreted to indicate 45 that the interchange of phenol with aluminum thiocresoxide is complete, and, under the distillation conditions, essentially irreversible.

The mechanism that occurs in the reactions of this invention is considered a highly complex one. While I 50 do not desire to have the scope of this invention restricted by any explanation proffered, it is considered apparent that the formation of aluminum phenoxide occurs because of a rapid and essentially irreversible interchange of the tar acids with the aluminum thiophenoxides to yield the corresponding thiophenols and aluminum phenoxides. This interchange occurs somewhat surprisingly despite the fact that thiophenol is a considerably stronger acid than phenol, and hence thiophenol might ordinarily be expected to be more reactive

55 than phenol. However, as shown herein, once this interchange is initiated not only is the selective reaction with phenol favored, but apparently the phenoxide will be formed to the complete exclusion of thiophenoxide as long as any phenol is present.

75 While this invention has been described with respect

to specific preferred embodiments, I do not desire to be limited by the illustrative examples given or the speculative mechanisms postulated for this reaction. The scope of this invention accordingly should be determined in accordance with the principles and claims thereof.

I claim:

1. The process for purifying a tar acid-contaminated thiophenol which comprises reacting a mixture of a thiophenol and a tar acid with an aluminum thiophenoxyde to react selectively with the tar acid to form an aluminum salt thereof and a thiophenol of said thiophenoxyde, and separating the thiophenol from said salt.

2. The process for recovering a thiophenol in substantially pure form from a mixture containing a thiophenol and a tar acid which comprises adding to said mixture under reactant conditions an amount of an aluminum thiophenoxyde sufficient to provide at least $\frac{1}{3}$ gram atom of aluminum per mole of tar acid present to react selectively with the tar acid to form an aluminum salt thereof and a thiophenol of said thiophenoxyde, and distilling off the thiophenol substantially free from tar acid.

3. The process according to claim 2 wherein said

aluminum thiophenoxyde is the aluminum salt of a thiophenol present in said mixture.

4. The process for recovering a thiophenol in substantially pure form from a mixture containing a major portion of a thiophenol and a minor portion of a tar acid which comprises reacting an amount of an aluminum thiophenoxyde sufficient to provide at least $\frac{1}{3}$ gram atom of aluminum per mole of tar acid present with said mixture at a temperature between 0 and 200° C. at which 10 a reaction occurs and an aluminum phenoxide and a thiophenol are formed, and distilling off the thiophenol from the mixture in substantially pure form.

5. The process for recovering a thiocresol in substantially pure form from a mixture containing a major portion of a thiocresol and a minor portion of cresol which comprises adding to said mixture under reactant conditions an amount of aluminum thiocresoxide sufficient to provide at least $\frac{1}{3}$ gram atom of aluminum per mole of cresol present to react selectively with the cresol 15 to form aluminum cresoxide and thiocresol, and distilling off the thiocresol substantially free from cresol.
